RAILWAY SIGNAL APPARATUS

Paul N. Bossart, Cheswick, Pa., assignor to The Union Switch & Signal Company, Swissvale, Pa., a corporation of Pennsylvania

Application August 30, 1941, Serial No. 409,046

17 Claims. (Cl. 246—130)

My invention relates to railway signal and communication apparatus, and it has particular reference to the organization of such apparatus into novel and improved systems for effecting control or communication by means of energy transmitted from a railway train or vehicle. More particularly, my invention relates to the organization of such apparatus into novel and improved systems for controlling traffic controlling or signal devices, located along the wayside, by means of energy transmitted to the trackway from a train.

In general, it is proposed in accordance with my invention to provide means on a train for impressing on a trackway, current having a frequency proportional to the train speed, and to provide means in the wayside receiving such current for effecting a control or controls in accordance with the frequency of the received current. More specifically, it is proposed to provide a system utilizing current impressed by a train on the trackway and having a frequency corresponding to the train speed, for controlling the operation of a warning device, such as a highway crossing signal, positioned along the wayside.

In systems for controlling highway crossing signals, it is advantageous to provide an adequate warning period during which operation of the crossing signal device is effected prior to the arrival of trains at the crossing, thereby to enable operators of vehicles on the highway to bring their vehicles to a stop short of the crossing. Ordinarily, the operation of the warning device is initiated when a train reaches a predetermined point in the rear of an intersection, and the operation of the signal is maintained until the train vacates the crossing. In order to provide an adequate warning interval under all conditions, the point at which operation of the signal is initiated must, of course, be so chosen as to provide a predetermined minimum warning interval for trains operating at the authorized maximum speed. This, however, tends to provide unnecessarily long warning periods for slower moving trains since such trains require considerably longer time to reach the crossing. For example, if the maximum authorized speed is of the order of 120 miles per hour and the point at which operation of the signal is initiated is selected to provide a minimum warning interval of, say, 20 seconds prior to the train arriving at the crossing, it is apparent that trains operating in the lower ranges of speed such as at 15 miles per hour, or one-eighth as fast as the maximum authorized speed, will require eight times as long

to travel from the point of initiation of the crossing signal operation to the crossing and hence will provide a warning period eight times as long as the minimum period, or some two minutes and forty seconds in duration. Such a warning interval provided for slow moving trains is obviously undesirable since it unduly and unnecessarily blocks or ties up vehicular traffic on the highway. In addition, such unduly long warning periods might cause motorists to disregard the warning when a train does not approach the crossing within a short time after the warning is initiated.

In view of the foregoing and other important considerations, it is an object of my invention to provide a novel and improved system for controlling highway crossing signals in such manner as to obtain a substantially uniform warning period of operation of the signal prior to a train reaching an intersection, irrespective of the speed of the train. Specifically, the system is organized in such a manner that in the normal range of the train speeds, such as from approximately 7½ to 120 miles per hour, inclusive, the warning period of operation of the crossing signal prior to arrival of a train at the crossing is never less than the predetermined minimum period and never greater than double such predetermined minimum period. In other words, the maximum period of operation effected prior to the arrival of a train at the crossing is never more than twice as long as the minimum warning period, hence the warning period is caused to be of a substantially uniform length irrespective of the train speed.

Another object of my invention is the organization of railway signal and communication apparatus into novel and improved systems for effecting a control or controls in the wayside in response to energy supplied by a train to the trackway.

A further object is the provision, in a system of the class above described, of means for selectively controlling a device in the wayside in accordance with the train speed.

An additional object is the provision of novel and improved systems for controlling highway crossing signals by energy applied to a trackway by a train.

Other important objects and characteristic features of my invention will become apparent from the following description.

I shall describe several forms of apparatus embodying my invention, and shall then point out the novel features thereof in claims.

In the accompanying drawings, Fig. 1 is a diagrammatic view illustrating the wayside portion of the apparatus embodying my invention. Figs. 2 and 3 are each diagrammatic views illustrating modifications of a portion of the apparatus represented in Fig. 1. Fig. 4 is a diagrammatic view illustrating the train-carried portion of apparatus embodying my invention. Fig. 5 is a diagrammatic view illustrating a modification of a portion of the apparatus represented in Fig. 4. Figs. 6 and 7 are each diagrammatic views illustrating modifications of portions of the apparatus represented in Fig. 1. In each of the several views, similar reference characters have been employed to designate corresponding parts.

As above stated, an object of my invention is to provide means controlled by energy impressed by a train on a trackway to provide a substantially uniform warning period of operation of a signal prior to the arrival of a train at a highway grade crossing. To effect this and other important objects of my invention, the wayside portion of the apparatus embodying my invention is applied, as shown in Fig. 1, to a stretch of railway track over which traffic normally operates in the direction indicated in the drawing by an arrow, or from left to right as viewed in Fig. 1. Intersecting the stretch at grade is a highway H, and provided at the railway-highway intersection are any suitable or desired forms of crossing signals or highway crossing warning devices, such as, for example, an audible signal S in the form of an electric bell. The track rails 1 and 1a are divided by means of the usual insulated joints 2 into a plurality of successive adjoining track sections J—K, K—L, L—M and M—N, which sections extend from the intersection in the direction of approaching trains so as to be traversed in the order named by eastbound trains approaching the crossing.

The entrance end J of the first section J—K traversed by a train approaching the crossing is located at a distance from the crossing equivalent to that traversed by a train operating at the maximum permissible speed for the predetermined minimum period selected for the crossing signal; the entrance end K of the second section, K—L, traversed by the train is located at a distance from the crossing substantially equivalent to that traversed by a train operating at one-half the maximum speed for the predetermined minimum operating period; the entrance end L of the third section, L—M, traversed by the train is located at a distance from the crossing equivalent to that traveled by a train operating at one-quarter the authorized maximum speed for the predetermined minimum operating period; and the entrance end M of the fourth section, M—N, is located from the crossing a distance substantially equivalent to that traversed by a train when operating at one-eighth the authorized maximum speed for the predetermined minimum operating interval.

Each of these track sections is provided with a track circuit comprising a suitable source of current, such as a track battery 3, and a track relay, designated by the reference character TR with a suitably distinguishing suffix, connected across the rails at the opposite ends of the section. The connection of relay TR1 is effected, as shown, over a circuit including in series front contacts 8 and 9 of relays TR2 and TR3, respectively, hence relay TR1 is released whenever a train occupies one or

more of the three sections J—K, K—L and L—M, and is thus responsive to traffic in each of the named three sections.

Associated with relay TR1 are two repeater relays TPR1 and TPR2, normally energized in series over an obvious circuit including front contact 10 of relay TR1 and a suitable source of current, such as a battery not shown but having its opposite terminals designated by the reference characters B and C. These repeater relays are, therefore, responsive to traffic conditions in each of the track sections J—K, K—L and L—M. Associated with the track relays TR1, TR2 and TR3 is a polarized relay PR provided with an energizing circuit completed when relay TR1 is released and relay TR3 is picked up. The circuit of relay PR includes pole changing contact members 12 and 15 of relay TR2, hence when the circuit of relay PR is completed, the relay is caused to operate its contact members to one extreme position such as to their left-hand positions, as viewed in the drawings, when relay TR2 is picked up to supply current of one relative polarity to the circuit, and such relay operates its contact members to their opposite extreme or right-hand positions in response to energy of the opposite polarity supplied to the circuit when relay TR2 is released. When the energizing circuit of relay PR is opened, as when relay TR1 is picked up or relay TR3 is released, the contact members of relay PR operate to their pendant or intermediate positions.

The track relays TR and the associated relays TPR1, TPR2 and PR, have associated therewith apparatus arranged so as to cause operation of the crossing signal S to be initiated when a train enters section J—K, K—L or L—M at a speed in excess of one-half, one-quarter and one-eighth the authorized maximum speed, respectively. That is to say, when a train approaches the crossing at a speed ranging between one-half and the full maximum authorized speed, operation of the signal is initiated when such train enters section J—K. If the train is operating at a speed varying between one-quarter and one-half the maximum authorized speed, the initiation of the operation of the signal is postponed or delayed, in a manner to be made clear presently, until the train enters section K—L. Should the train be operating at a speed varying between one-eighth and one-quarter of the maximum authorized speed, operation of the signal is then postponed until the train enters section L—M; while if the train is operating at a speed less than one-eighth of the maximum speed, operation of the signal is then initiated when section M—N is entered.

The above described control of signal S is effected by means of an operating circuit provided for the signal and controlled by the track relays TR and by means receiving energy impressed by a train on the trackway and selectively responsive to the frequency of the received current. The operating circuit of signal S comprises two alternate paths, one path of which includes back contact 17 of relay TR4 and a source of current, and the other path of which extends from terminal B through back contact 18 of relay TPR2, back contact 19 of a control relay CR, to be referred to hereinafter, and signal S to the other terminal C. It is apparent, therefore, that operation of signal S is effected whenever relay TR4, associated with section M—N, is released, and that operation of the signal may be effected whenever relay TPR2, controlled by traffic in sec-

tions J—K, K—L and L—M, inclusive, is released provided that control relay CR also is released.

Relay CR has associated therewith wayside apparatus comprising means for deriving from the trackway energy applied thereto from a train, and decoding means operated by such receiving means for controlling relay CR in accordance with the frequency of the received energy. Such receiving means, as shown, comprise conductors, one of which, conductor 21, is connected at 22 to rail 1 of section M—N and extends parallel to the rail a short distance in either direction, while the other conductor 23 is connected at 24 to track rail 1a of section M—N and likewise extends in either direction parallel to such rail a short distance, of the order of 100 to 200 feet. Each conductor is grounded at each end and is tuned, as by condensers 25, to a predetermined or desired frequency. Adjacent the point of connection of the conductors to the track rails are provided loops, preferably having a single turn, which are coupled to pick-up coils 26 tuned by condensers 27 to a frequency corresponding to the predetermined frequency.

Alternate means for coupling the pick-up coils 26 to the trackway may be employed and are shown in Figs. 2 and 3. In Fig. 2 a pick-up coil 26 is disposed in the trackway in inductive relationship with both track rails 1 and 1a. In Fig. 3, pick-up coil 26 is inductively coupled with a loop formed in a wayside conductor 29 disposed adjacent the track rails and extending from the crossing to the entrance end of section J—K, first to be entered by a train approaching the crossing. This wayside conductor 29, grounded at each end, is preferably tuned, as by condensers 30, to a frequency corresponding to the predetermined frequency hereinbefore mentioned, and may be utilized to transmit along the trackway current of a predetermined frequency applied from a train or vehicle to the trackway in a manner to be made clear presently.

Use of the conductor 29 is optional and may, if desired, be either dispensed with or employed in connection with impedance networks provided at the adjacent ends of each two adjoining track sections. These impedance networks comprise a pair of impedance elements 31 connected respectively across the track rails at the adjacent ends of two adjoining track sections, and which pair of elements are center-connected so as to transmit around the associated pair of insulated joints 2 energy flowing in the rails in multiple, but which impedance networks are effective to prevent track circuit energy, flowing through the rails in series, from being transmitted around the joints from one section into the adjoining section. The impedance networks are, therefore, effective to transmit through the trackway and around the insulated joints 2 energy applied from a train to the two rails of the trackway in parallel.

The decoding apparatus hereinbefore mentioned comprises an amplifier-demodulator-filter unit ADF, a plurality of relays, designated by the reference character R with suitably distinguishing prefixes, associated with unit ADF; a chain of relays RC, a frequency responsive relay FR, a checking relay CCR, and control relay CR. The details of construction of the amplifier-demodulator-filter unit are not shown in the drawing, but such unit may be similar, for example, to units of the type shown in United States Letters Patent No. 2,064,639 granted on

December 15, 1936, to Leland C. Whitelock et al., and employed in train communication systems for amplifying, demodulating and filtering current supplied to the trackway. Unit ADF, however, differs from the usual amplifier-demodulator-filter units in that it incorporates two call units, one unit U1 being tuned to a first frequency of modulation and the other unit U2 being tuned to a second frequency of modulation impressed on the current received from the track rails.

The amplifier-demodulator-filter unit ADF is connected by wires 35 and 36 to pick-up coils 26, and it incorporates the usual electron tube amplifiers which may have their plate circuits energized, as indicated in the drawing, only when relay TPR is released to close its back contact 37. However, if desired, such plate circuits may be steadily energized. One relay 3R is connected to the output terminals of call unit U2 of the unit ADF, and hence is energized during the interval that current modulated at the second frequency is received by the unit from the trackway.

25 The other call unit U1 supplies energy to two relays 1R and 2R, which relays accordingly are picked up when current modulated at the first frequency is received by the amplifier-demodulator-filter unit ADF.

30 The relay chain RC, as shown, comprises a plurality of relays 40, 41, 42 and 43. One relay 40 functions as an impulsing relay for a purpose to be made clear presently, and is caused to operate at a rate dependent upon the rate 35 of operation of relay 1R and the position of polarized relay PR. When relay PR is energized by current of one polarity and its polar contact members are in their left-hand positions, as viewed in the drawing, the four relays of the 40 chain are sequentially energized or operated, and relay 40 is caused to operate at a rate one-quarter as fast as relay 1R. When relay PR operates its contact members to their right-hand positions, relays 40 and 43 are alternately 45 operated and relay 40 accordingly operates at a rate one-half that of relay 1R. When relay PR is deenergized, relay 40 functions as a simple repeater of relay 1R and accordingly operates at a rate corresponding to that of relay 1R.

50 Frequency responsive relay FR comprises two windings, one winding 44 of which is energized, in series with a portion of winding 46 of a transformer 47, over an obvious circuit including the source of current and front contact 48 of impulsing relay 40. The other winding 45 of relay FR is energized, in series with another portion of the winding 46, over an obvious circuit completed when back contact 49 of relay 49 is closed. The two portions of winding 46 are disposed so as to create opposing fluxes when energized, hence it follows that the flux in transformer 47 is caused to reverse at a rate proportional to the rate of operation of relay 40. The two windings 44 and 45 of relay FR are arranged so that when 55 the windings are alternately energized, contact member 50 of the relay is reversibly operated from one extreme position to the other, and the windings of the relay and the proportioning of the transformer 47 are so selected and proportioned that each winding 44 and 45 is effectively energized only when the rate of flux reversal in transformer 47 does not exceed a predetermined rate.

60 Control relay CR also comprises two windings, one winding 51 of which is energized by current derived from secondary winding 49 of trans-

former 47 and at times such current is caused to be substantially unidirectional in character due to the rectifying action of contact 59 of relay FR. That is to say, when flux having a given direction is present in transformer 47, current of one relative polarity is induced in one portion of winding 49 and is supplied over contact 59 of relay FR, in one position of the relay, to winding 51 of relay CR. Then, when the direction of flux in the transformer is reversed so that current of the opposite relative polarity is induced in the other portion of secondary winding 49, and if the rate of flux reversal is within that which relay FR follows, contact 59 is swung to its other position to cause the current induced in secondary winding 49 to flow through winding 51 in the direction corresponding to the current flow through the relay when contact 59 of relay FR is in its one position.

A checking relay CCR also is provided, together with a ballast lamp BL, for a purpose to be made clear in the following description.

The train-carried portion of the apparatus embodying my invention is represented in Fig. 4 as being provided on the locomotive and its associated tender, but it is to be understood of course that such apparatus may be provided on any desired railway vehicle. This apparatus, as shown, includes means for impressing on the track rails current having a frequency proportional to the train speed, and it comprises a transformer 60, a source of oscillations of the predetermined or desired frequency, preferably of the order of 1000 to 10,000 cycles per second, and means for modulating the output of the source of oscillations at a rate proportional to the train speed. The source of oscillations may, for example, comprise an inductor alternator HFG incorporated into the usual locomotive headlight generator LHG, and the output terminals of such inductor alternator are connected across the terminals of primary winding 61 of transformer 60 in series with a modulating contact of modulating device MD70 or MD105, respectively. These modulating devices may, for example, comprise tuned alternators effective to operate at relatively low frequencies of, say, 70 and 105 cycles per second, respectively, and first one and then the other of the two devices is rendered effective to modulate the output of the conductor alternator, at a rate proportional to the train speed, by means of a suitable switch or commutator SW attached to or driven by an axle of the vehicle at a rate dependent upon the vehicle speed. As shown, the switching means SW is mounted on an axle and comprises four contact elements disposed 90° apart and mounted to engage the peripheries of a contacting surface 66 formed on the axle. One-half or 180° of the contacting surface 66 comprises a conducting material, and the other half comprises an insulating material. The arrangement of the modulating contacts, inductor alternator HFG, and contact elements of the switching means SW, as illustrated in Fig. 4, is such that during one-half of each revolution of surface 66, contact 70 of device MD70 is interposed in series in the connection of inductor alternator HFG to winding 61 of transformer 60, and during the other half of each revolution contact 105 of the other modulating device MD105 is interposed in such circuit connection. Such an arrangement obviously is effective to cause the two modulating devices to modulate the output of the inductor alternator alternately during the opposite half revolutions of surface 66.

In a modified arrangement of the modulating contacts, inductor alternator HFG, and contact elements of the switch SW represented in Fig. 5, the arrangement is such that one of the modulating contacts is shunted during one-half of the revolution of contacting surface 66, and the other contact is shunted during the other half of such revolution. In such an arrangement, contact element 64 is connected to one terminal of inductor alternator HFG, the other contact element 62 disposed 180° from element 64 is connected through winding 61 of transformer 60 to the other terminal of the inductor alternator, and the other two contact elements 63 and 65 are connected together by a jumper 67. Modulating contacts 70 and 105 of modulating devices MD70 and MD105 are connected, in series, directly across contact elements 62 and 64, and a connection is established from the other two contacting elements 63 and 65 to the series circuit connection of the modulating contacts, at a point intermediate such contacts. It is apparent that when the contacting portion of surface 66 is in the upper half, as viewed in the drawing, of its revolution, so that contact element 62 is in engagement therewith, a circuit is established from one terminal of inductor alternator HFG through contact 70 of modulating device MD70, contact element 63 or 65, conducting portion of surface 66, contact element 62 and winding 61 of transformer 60 to the opposite terminal of inductor alternator HFG, with the result that in this portion of the revolution of surface 66, the output of the inductor alternator is caused to be modulated by contact 70. During the other half of the revolution of surface 66 when the conducting portion of the surface is in engagement with contact element 64, a circuit is then established from one terminal of inductor alternator HFG through contact element 64, the conducting portion of surface 66, either contact element 63 or 65, contact 105 of modulating device MD105, and winding 61 of transformer 60 to the other terminal of the inductor alternator, whereupon the output of the inductor alternator is caused to be modulated by contact 105. It follows, therefore, that the output of inductor alternator HFG is caused to be modulated at first one frequency during one-half of the revolution of member 66 and is modulated at another frequency during the other half of such revolution.

The output of inductor alternator HFG, modulated in the manner pointed out heretofore, is impressed upon the rails of the track longitudinally by means of a circuit which connects one terminal of secondary winding 69 of transformer 60 to one of the hubs or axles of the tender, and which connects the opposite terminal of winding 69 to one of the hubs or axles of the locomotive. These axles are preferably insulated from each other, thus causing the rails in their longitudinal direction to form a part of the output circuit of transformer 60. Interposed in such output circuit is a tuning condenser 71 and a switch 72, the latter of which when opened functions to interrupt the output circuit of transformer 60. Switch 72 also functions to control the operation of the modulating devices MD, which devices are energized by current supplied from any suitable source, such as the direct current generator LHG, over an obvious circuit completed when switch 72 is closed.

Normally, the wayside portion of the apparatus embodying my invention hereinbefore described is in its normal condition as represented

in Fig. 1, when sections J—K, K—L, L—M and M—N are unoccupied. In this condition of the apparatus, the several track relays TR are picked up and repeater relays TPR1 and TPR2 are energized, so that signal S is deenergized, while polar relay PR is likewise deenergized. Relays R associated with unit ADF are released, impulsive relay 40 is energized over a circuit extending from terminal B through back contact 75 of relay 43, the upper winding of relay 40 and back contact 76 of relay 1R to terminal C; but the other relays of the chain RC are released. Winding 44 of relay FR is energized over an obvious circuit extending from terminal B through ballast lamp BL, a portion of winding 46 of transformer 47, winding 44 of relay FR and front contact 48 of relay 40 to terminal C, and contact 50 of relay FR accordingly is caused to swing to its left-hand position, as viewed in the drawing. The flux of transformer 47 is at a substantially constant state condition, hence there is no energy induced in winding 49 so that winding 51 of control relay CR is deenergized and the relay is released. Checking relay CCR is, however, in its normally energized condition.

With the wayside apparatus in its normal condition, a train or vehicle may operate on the track outside the limits of the stretch J—N, and apply energy to the track rails without affecting the wayside apparatus since such trackway transmitted energy is substantially blocked by joints 2 at J (which joints are not by-passed by an impedance network), and also since any energy picked up by coils 26 and supplied to unit ADF is ineffective to cause operation of the associated relays due to the fact that the plate circuits of the unit are open at back contact 37 of relay TPR1, and as a result the apparatus of the filter is inactive.

When, however, a train or vehicle enters section J—K and shunts relay TR1, repeater relay TPR1 releases to close its back contact 37 and thereby render active unit ADF, while repeater relay TPR2 also releases at the end of its slow release interval. If the train or vehicle does not impress on the trackway, energy of the predetermined frequency modulated at a rate proportional to the train speed, as for example when such vehicle is not equipped with apparatus similar to that hereinbefore described and illustrated in Fig. 4, or if a vehicle equipped with such apparatus enters the section with switch 72 open, then at the end of the slow release interval of relay TPR2, back contact 18 closes to complete for signal S the previously traced energizing circuit extending through back contacts 18 and 19 of relay TPR2 and CR, respectively, with the result that operation of signal S is initiated. Operation of the signal, under the assumed conditions, is maintained until the train or vehicle clears the crossing.

If, however, a vehicle or train enters section J—K and impresses on the trackway energy of the predetermined frequency modulated in accordance with the train speed, then the wayside apparatus functions to delay initiation of operation of signal S if the train operates at a speed below a predetermined speed but not if the train speed is above such predetermined speed. As mentioned heretofore, the particular arrangement of the wayside apparatus illustrated in Fig. 1 is such that when a train enters the section J—K at a speed in excess of one-half its authorized maximum speed (assumed to be 120 miles per hour), the operation of signal S is then ini-

tiated, whereas if the train speed is less than one-half the authorized speed, the operation of the signal is delayed until another section nearer the intersection is entered.

With the train in section J—K impressing on the trackway, energy modulated alternately at the first and second modulation frequencies and at a rate proportional to the train speed, relays 2R and 3R associated with unit ADF are alternately energized and deenergized, the first relay 2R being energized in response to the alternate intervals during which energy modulated at the first frequency is received from the trackway, and the other relay 3R being energized in response to the opposite alternate intervals during which energy modulated at the second frequency is received from the trackway. These relays are, however, provided with slow release characteristics so that each relay remains in its picked-up position unless the modulating energy occurs at the rate or frequency corresponding to a very low train speed of the order of about, say, 5 miles per hour or less. It follows, therefore, that both relays 2R and 3R are energized when a train operates on the trackway at a speed above such low speed. The purpose of the relays 2R and 3R will be made clear presently.

The other relay 1R associated with unit ADF is likewise alternately energized and deenergized in step with the alternate intervals during which energy modulated at the first modulation frequency is received from the trackway, and relay 1R is arranged to respond to such energy by picking up in response to each interval during which energy of the first modulation frequency is received from the track rails, and by releasing during each of the other intervals during which energy of the other or second modulation frequency is received. Contacts 76 of relay 1R accordingly is operated at a rate corresponding to the rate at which the intervals of the first modulation frequency are received, or at a rate corresponding to the speed of the vehicle.

When the train occupies section J—K, polar relay PR is energized over its previously mentioned circuit by current having a polarity such that it causes contact members 30 and 31 of the relay to assume their left-hand positions, whereupon impulsive relay 40 is energized and the relay chain RC associated with relay 1R is conditioned to cause impulsive relay 40 to operate at a rate corresponding to one-quarter of the rate of operation of relay 1R. Each of the relays of the chain is provided with two windings, an upper or pick-up winding and a lower or stick winding, and the relay chain is arranged in such manner that the pick-up winding of impulsive relay 40 is energized over a back contact of relay 43, while the pick-up winding of relays 41, 42 and 43 are energized over front contacts of relays 40, 41 and 42, respectively. The arrangement is such that the circuits of the pick-up and stick windings of the relays are so controlled by contact 76 of relay 1R that the four relays 40, 41, 42 and 43 are first sequentially energized in the order named and are then deenergized in the same order, each operation of contact 76 of relay 1R being effective either to energize or deenergize one of the relays.

Specifically, the arrangement is such that the pick-up winding of relay 40 is normally energized, when the wayside apparatus is inactive and the track sections are all unoccupied, over a circuit including back contact 75 of relay 43 and back contact 76 of relay 1R. When section J—K

becomes occupied and relay TR1 drops to close its back contacts 11 and 16 to cause relay PR to swing its polar contact members 80 and 81 to their respective left-hand positions, and when relay 1R closes its front contact 76 in response to the first interval of energy modulated at the first frequency received by unit ADF, the stick winding of relay 40 is energized over a circuit extending from terminal B through front contact 82 of relay 40, polar contact 80 of relay TR in its left-hand position, the lower winding of relay 40 and front contact 76 of relay 1R to terminal C; and the pick-up winding of relay 41 is energized over a circuit extending from terminal B through front contact 83 of relay 40, polar contact 81 of relay TR closed in its left-hand position, the upper or pick-up winding of relay 41 and front contact 76 of relay 1R to terminal C. Relay 41 accordingly picks up and closes its front contact 84 so that when relay 1R releases to close its back contact 76, the pick-up winding of relay 40 then is energized over a circuit previously traced, and the stick winding of relay 41 is energized over a circuit including front contact 84 and the lower or stick winding of the relay as well as back contact 76 of relay 1R. In addition, the pick-up winding of relay 42 is energized over a circuit extending from terminal B through front contact 85 of relay 41, the upper or pick-up winding of relay 42 and back contact 76 of relay 1R to terminal C, whereupon relay 42 picks up to close its front contact 86. When relay 1R again picks up to close its front contact 76, the stick winding of relay 42 is energized over an obvious circuit including its own front contact 86 and its lower or stick winding as well as front contact 76 of relay 1R; the stick winding of relay 40 and the pick-up winding of relay 41 are also energized; and relay 43 is energized over a circuit extending from terminal B through front contact 87 of relay 42, the upper or pick-up winding of relay 43 and front contact 76 of relay 1R to terminal C, whereupon relay 43 picks up to close its contact 75. When relay 1R again drops to close its back contact 76, the lower or stick winding of relay 43 is energized over an obvious circuit including its front contact 75 and the lower or stick winding of relay 43 as well as back contact 76 of relay 1R; the stick winding of relay 41 and the pick-up winding of relay 42 are likewise energized; and relay 40 releases since its stick circuit is open at front contact 76 of relay 1R and its pick-up circuit is open at back contact 75 of relay 43. When relay 1R again picks up to close its front contact 76, relay 41 becomes deenergized and releases, and when relay 1R again releases, relay 42 becomes deenergized and releases. Relay 43 also releases when relay 1R picks up following the release of relay 42, and relay 43 accordingly closes its back contact 75 to prepare the pick-up circuit of relay 40, which circuit is made effective upon the subsequent release of relay 1R to pick up relay 40 and initiate the operation of the relays in the relay chain. It follows, therefore, that when the train occupies section J-K, impulsive relay 40 is caused to operate its contact member 48 at a rate corresponding to one-fourth the rate of operation of relay 1R.

Each operation of contact 48 of impulsive relay 40 reverses the direction of flux in transformer 47, and causes one winding 44 or the other winding 45 of relay FR to be energized. The windings of relay FR and transformer 47 are selected so that when relay 40 operates at a rate corre-

sponding to a speed less than one-half of the authorized maximum speed (or a speed of less than 60 miles per hour), and the direction of flux is reversed in transformer 47 at one-fourth of such rate of operation of relay 1R, the two windings 44 and 45 of relay FR are effectively energized and cause contact member 50 to be operated alternately to its left-hand position and then to its right-hand position at a rate corresponding to the rate of flux reversal in the transformer. This operation of contact member 50 of relay FR causes the alternating current induced in secondary winding 49 of transformer 47 to be supplied to winding 51 of relay CR as substantially unidirectional current, and relay CR accordingly is energized. If, however, relay 1R operates at a rate corresponding to a train speed of more than 60 miles per hour and the flux in transformer 47 is reversed at a rate corresponding to one-fourth of such rate, the impedance of winding 46 is caused to build up to a value such as to limit the flow of current in windings 44 and 45 of relay FR to a value insufficient to effectively energize the relay, and its contact member 50 accordingly is held stationary. The current induced in winding 49 of transformer 47 is, therefore, supplied to relay CR as alternating current, and relay CR accordingly is caused to remain released.

30 The previously mentioned slow release interval of relay TPR2 is selected so that prior to the release of the relay, the wayside apparatus is enabled to pick up relay CR if the train in section J-K is operating at a speed less than one-half its maximum speed. It follows, therefore, that when relay TPR2 releases at the end of its slow release interval, operation of the signal is initiated if relay CR is not picked up due to the train operating in excess of 60 miles per hour, but if the train operates at a speed less than 60 miles per hour, the operation of the signal is postponed.

40 If the operation of the signal is initiated by a train entering section J-K at a speed in excess of 60 miles per hour, such operation is maintained until the train clears the crossing. If, however, operation of the signal is not initiated when section J-K becomes occupied, the signal is set into operation when the train enters section K-L if the train operates at a speed in excess of one-fourth the authorized speed (or a speed in excess of 30 miles per hour), but is not initiated if the train speed is less than the predetermined speed of 30 miles per hour.

55 For example, I shall assume that a train approaches the crossing at a speed less than 60 miles per hour so that the wayside apparatus functions in the manner described to postpone operation of the signal when relay TPR2 releases. When the train enters section K-L, relay TR2 releases to close its back contacts 12 and 15 and pole change the current supplied to relay PR, whereupon relay PR shifts its contacts to their right-hand positions and conditions the relay chain RC to cause impulsive relay 40 to operate at a rate corresponding to one-half the rate of operation of relay 1R. With polar contacts 80 and 81 of relay PR in their respective right-hand positions, the pick-up and stick circuits of relay 40 and the stick circuit of relay 43 remain as traced hereinbefore, but the pick-up circuit of relay 43 is completed over front contact 83 of relay 40 and the polar contact member 81 of relay PR closes in its right-hand posi-

tion, hence only the two relays 40 and 43 are sequentially energized and relay 40 is caused to operate at a rate corresponding to one-half the rate of operation of relay 1R. Relay FR accordingly is effectively energized only if the reversal of flux in transformer 47 occurs at a rate corresponding to the predetermined rate, but since relay 40 now operates only one-half and not one-quarter as fast as relay 1R, the upper limit of the train speed accordingly is shifted from 60 to 30 miles per hour, so that if the train operates at a speed in excess of 30 miles per hour, relay FR is ineffectively energized and relay CR releases to initiate operation of signal S. If, however, the train speed is below 30 miles per hour, then relay FR is effectively energized and relay CR also is energized to again postpone operation of the signal.

Assuming, for example, that the train in section K-L operates at a speed less than 30 miles per hour, operation of signal S is not effected when the train enters section K-L. In such event, operation of the signal may be effected when the train enters section L-M provided that the train operates at a speed greater than 15 miles per hour, but such operation is not initiated when a train operates at a speed less than 15 miles per hour.

When the train enters section L-M, relay TR3 releases and opens its front contacts 13 and 14 to deenergize relay PR whereupon contact members 80 and 81 of such relay assume their pendant positions to condition relay 40 to operate at a rate corresponding to the rate of operation of relay 1R, and since relay 1R now operates at a rate corresponding to the rate of operation of relay 1R and not at a rate corresponding to one-half of the rate of relay 1R, the upper limit of the train speed accordingly is shifted from 30 to 15 miles per hour. It follows that if the train operates at a speed in excess of 15 miles per hour, relay FR is ineffectively energized and relay CR releases to initiate operation of signal S. If, however, the train speed is below 15 miles per hour, then relay FR is effectively energized and relay CR also is energized to again postpone operation of the signal.

In the event that a train approaches the crossing at a speed less than 15 miles per hour so that operation of the signal is not initiated when section L-M is entered, the signal is set into operation irrespective of the train speed when section M-N is entered and relay TR4 releases to close its back contact 17. If, however, such train slows down to a very low speed or comes to a stop prior to entering the positive operating section M-N, the rate of operation of contact 72 by relay 1R may then be insufficient to cause the energy induced in winding 49 and supplied to relay CR to reach a value sufficient to maintain relay CR picked up to thereby prevent operation of the signal. To preclude the possibility of causing operation of the signal with the train stopped short of section M-N, the slow-speed and slow-acting relays 2R and 3R are provided with control means for providing an energizing circuit for relay CR whenever either relay 1R or 2R is picked up and the other relay is released. When the train is stopped so that only energy modulated at one of the modulation frequencies is constantly impressed along the trackway, one or the other of the two relays 2R and 3R is picked up while the other relay is released, so that relay CR is maintained energized over a circuit ex-

tending from terminal B through ballast lamp BL, the upper winding 52 of relay CR, and front contact 90 of relay 3R and back contact 91 of relay 2R, or back contact 92 of relay 3R and front contact 93 of relay 2R, to terminal C. The energization of relay CR, under the conditions assumed, prevents operation of the signal. The slow releasing characteristics of relays 2R and 3R are selected, however, so that when alternate intervals of energy modulated at the first and the second modulation frequencies are received at a rate sufficient to enable transformer 49 to effectively energize relay CR, both relays 2R and 3R are held constantly picked up and hence are not effective to assist in energizing relay CR under such conditions.

Fig. 6 represents a portion of the apparatus illustrated in Fig. 1 modified in such manner as to provide safeguards against improper operation of the slow-speed relays associated with unit ADF. In Fig. 6, relays 2R1 and 3R1 are employed and are controlled so as to preclude the possibility that one of the relays might remain up and the other relay remain down due to a failure in their respective control circuits, or to a failure of the apparatus on the train supplying energy to the trackway. These relays control a circuit, substantially similar to that provided by relays 2R and 3R of Fig. 1, for energizing relay CR when a train stops or slows down to a very low speed in section J-K, K-L or L-M prior to entering the positive operation section M-N.

Referring now to Fig. 6, relay 2R1 as shown comprises three windings 100, 101 and 102, while relay 3R1 comprises two windings 103 and 104. A continuity transfer or make-before-break contact arrangement is provided on relay 1R, and in the mid stroke position of the armature of relay 1R, a bifurcated or bridging member 106 of relay 1R engages both its associated front and back contact points to thereby complete an obvious energizing circuit for winding 100 of relay 2R1 when back contact 107 of relay 3R1 is closed. This circuit includes a suitable source of current, such as a battery 108. Winding 102 of relay 2R1 is provided with a short circuit path including contact 109 of relay PR in its right-hand, left-hand or dependent position, and an asymmetrical unit 110 arranged to short circuit the winding for current caused to be induced therein due to a decay of flux in the relay but not for current induced in winding 102 due to a growth of flux in the relay. The short-circuit path provided for winding 102 accordingly is effective to make relay 2R1 slow to release, but does not materially affect its pick-up characteristics. The other winding 101 of relay 2R1 is provided with a circuit extending from call unit U1 of the unit ADF through either front contact 111 of relay 2R1 or front contact 112 of relay 3R1, the winding 101 of relay 2R1 and contact member 109 of relay PR in any one of its three positions, to the other output terminal of unit U1.

The other relay 3R1 has its winding 103 provided with an energizing circuit extending from one output terminal of call unit U2 of unit ADF through either front contact 113 of relay 3R1 or front contact 114 of relay 2R1, winding 103 of relay 3R1, and contact member 115 of relay PR closed in any one of its three positions, to the other output terminal of unit U2. The other winding of this relay has a short circuit path completed through polar contact member 115 of relay PR closed in any one of its three positions

and including asymmetrical unit 116 arranged so as to make the relay slow to release.

Normally, both slow-speed relays 2R1 and 3R1 are released when filter unit ADF is inactive. If, now, energy is applied to the trackway from a very slow moving train, unit ADF becomes active due to energy received from the trackway, and relay 1R picks up when the first interval of energy modulated at the first modulation frequency is received, to cause winding 100 of relay 2R1 to become energized during the travel of the armature of relay 1R from its back to its front point. Relay 2R1 accordingly picks up, and closes its front contact 111 to energize its other winding 101, which winding holds relay 2R1 energized until the modulation frequency changes to that of the second frequency. When that happens, relays 1R and 2R1 become deenergized, and during the slow release interval of relay 2R1, winding 103 of relay 3R1 becomes energized to close its front contact 113 and provide a circuit which holds relay 3R1 up while energy of the second modulation frequency is received from the trackway. Back contact 107 of relay 3R1 also opens to open the circuit over which winding 100 of relay 2R1 is initially energized. Then, when the modulation frequency is shifted back to the first frequency, winding 101 becomes energized over front contact 112 of relay 3R1 during the slow release interval of the relay, and relay 2R1 closes its front contact 111 to complete the previously traced circuit which holds that relay energized during the interval that energy modulated at the first frequency is received from unit ADF after relay 3R1 releases. This action of the two relays in alternately becoming energized and released is continued as long as the slow moving train impresses energy on the trackway, hence such action of the relays is effective to hold relay CR energized to prevent operation of signal S when the train occupies any one of sections J-K, K-L or L-M, respectively.

The relays 2R1 and 3R1 are arranged so that if the energy applied to the trackway is modulated at a rate corresponding to a speed in the normal range of operating speeds of a train, the relays 2R1 and 3R1 will be both held continuously energized, due to the alternate periods of the two modulated frequencies occurring for intervals shorter in duration than the slow release intervals of the relays. In such event, the relays 2R1 and 3R1 accordingly do not function to control relay CR, which relay is then controlled through relay PR, relay chain RC, frequency responsive relay FR, and transformer 47, in the manner pointed out in detail heretofore.

To preclude the possibility that, due to a failure in the elements of either the train-carried transmitting apparatus or the wayside receiving apparatus, current modulated at only one of the modulation frequencies is supplied from unit ADF, when the train traverses the stretch at a relatively rapid rate of speed, the initial circuit for energizing relay 2R1 is carried through a continuity transfer contact on relay 1R, and the energizing circuits for relays 2R1 and 3R1 are carried through contacts of relay PR. Thus, should the energy be modulated at only the second frequency, then relay 1R is not picked up, and neither relay 2R1 nor 3R1 is energized so that no control of relay CR is effected, either by the slow speed relays 2R1 and 3R1 or by the relay chain RC and the frequency responsive relay FR.

If, on the other hand, current modulated at

only the first frequency is impressed by a moving train on the trackway, relay 1R is caused to pick up when the train enters section J-K, and winding 100 of relay 2R1 accordingly becomes energized to cause the relay to pick up and close its front contact 111, whereupon winding 102 of relay 2R1 becomes energized over its own front contact and polar contact 109 of relay PR in its pendant position (the normal position of such relay contact). Relay PR is made sufficiently slow acting that relay 1R is able to reach its full attracted position to deenergize winding 100 of relay 2R1, prior to contact member 109 of relay PR being swung to its left-hand position due to the energization of the relay by current of the polarity supplied thereto when section J-K becomes occupied. When, therefore, contact member 109 of relay PR is operated to its left-hand position, the energizing circuit of winding 101 is interrupted during the interval that member 109 is intermediate its dependent and its left-hand positions. At this time, the short circuit path provided for winding 102 is likewise open, hence relay 2R1 is made quick to release and consequently releases to open its front contact 111 and deenergize winding 101, prior to contact member 109 of relay PR reaching its left-hand position. Both slow speed relays 2R1 and 3R1 are deenergized, and if relay 1R is held constantly energized due to current modulated at the first frequency received from the track rails, neither the slow speed relays 2R1 and 3R1 nor the frequency responsive relay FR are effective to energize relay CR, whereupon that relay releases to initiate operation of signal S. It follows, therefore, that the arrangement of the apparatus shown in Fig. 6 provides safeguards to assure that a failure of the train or receiving apparatus cannot improperly prevent operation of signal S.

In addition, it is to be noted that the apparatus of Fig. 6 is arranged so as to check against possibility of failure of either or both the train and receiving apparatus after the train enters the section. In such event, if energy of but one modulation frequency is supplied from unit ADF, the passage of the train over the insulated joints 2 at K or L, causes operation of contact members of relay PR and thereby functions to open the energizing circuit of winding 101 or 103 of relays 2R1 or 3R1, respectively, as the case may be, to insure against such windings being improperly energized.

Should the train stop in any section, however, no operation of relay CR is then effected after the supply of energy is maintained at a single modulation frequency, and the slow speed relays accordingly are properly affected to prevent operation of the signal.

In the circuit arrangement shown in Fig. 6, the slow speed relays are slow releasing under normal conditions and there is a tendency for each relay to hold up over a front contact of the other relay when energy is alternately modulated at the two frequencies at a rate exceeding the rate at which either of the two relays drops out when deenergized. If desired, the arrangement may be modified to cause both slow speed relays to be both released when the upper speed limit of their operation is exceeded, and such a modified arrangement of the apparatus is represented in Fig. 7.

In Fig. 7, slow speed relay 2R2 has a pick-up winding 120 and a holding winding 121, and relay 3R2 has a pick-up winding 122 and a holding

winding 123. A transformer 124 is provided and has its primary winding 125 energized over an obvious circuit including front contact 126 of relay 1R and a suitable source of current such as a battery 127. When relay 1R is released, back contact 126 closes and replaces battery 127 by a resistor 128 selected to have a resistance substantially equal to the internal resistance of the battery so as to maintain substantially constant the resistance of the primary circuit of the transformer.

When relay 1R picks up, an impulse of energy is supplied from secondary winding 129 of transformer 124 to winding 126 of relay 2R2 through a circuit including asymmetrical unit 130 in its low resistance direction, and contact member 109 of relay PR in any one of its three positions. When relay 1R releases, an impulse of energy is supplied from the other secondary winding 131 of transformer 124 to winding 122 of relay 3R2 over a circuit including asymmetrical unit 132 arranged in its low resistance direction, and contact member 115 of relay PR in any one of its three positions. The energizing circuit for the holding winding of relay 2R2 is carried through its own front contact 133 and back contact 134 of the other relay 3R2, as well as contact member 115 of relay PR, while the circuit of holding winding 123 of relay 3R2 passes through its own front contact 135 as well as back contact 136 of relay 2R2 and contact member 109 of relay PR.

When the rates at which the alternate impulses of the two different modulation frequencies are supplied from unit ADF are relatively low, then relays 2R2 and 3R2 are alternately energized and deenergized and function as slow speed relays in much the same manner as relays 2R and 3R of Fig. 1, and relays 2R1 and 3R1 of Fig. 6. The relays are slow to pick up due to their holding windings being short circuited in the direction to provide slow pick-up characteristics, hence when the speed of the impulses actuating relay 1R is increased, the relays will both be released since the time constants of the circuit supplying energy to the transformer and from the transformer to the relay are such that the current supplied to the relays under the assumed conditions does not reach a value sufficient to pick up the relays. Similarly, under the conditions assumed, the energy supplied to a holding winding over a front contact of its own partner relay is not sufficient to maintain such relay energized when the partner relay releases, so that both relays become released and remain released as long as the impulses of energy actuating relay 1R occur at a relatively rapid rate. It follows, therefore, that relays 2R2 and 3R2 function as slow speed relays when relay 1R operates at a relatively low rate of speed, but that both relays are released when relay 1R operates at a relatively rapid rate of speed.

The lamp BL, shown in Figs. 1, 6 and 7, preferably is a ballast lamp of any suitable and well-known construction and comprising, for example, a filament formed of a material, such as iron wire, mounted in a sealed envelope and having the characteristics of changing its resistance with changes in the voltage applied thereto. Checking relay CCR preferably has its winding formed of a material having a substantially zero temperature coefficient of resistance. The lamp BL and relay CCR function to maintain at a substantially constant value the voltage applied to the frequency responsive relay FR, thereby to cause the apparatus including relay FR to have

substantially constant operating characteristics over a relatively wide range of voltage and temperature variations. Relay CCR is adjusted to release, and close its back contact 20 to complete an obvious energizing circuit for signal S, should the voltage available drop to a value below that necessary for proper operation of the frequency responsive relay FR.

It is, of course, to be understood that while the apparatus embodying my invention has been illustrated and described with reference to certain specific values of, say, train speeds, ratio of maximum to minimum warning periods, and number of involved track circuited sections, the values specified are merely illustrative and may be varied, within limits of course, to best suit the particular conditions met in practicing the invention.

From the foregoing description, it is readily apparent that I have provided novel and improved systems for controlling wayside apparatus in accordance with the speed of a train on a track, by means of energy applied by a train to the trackway. It is also apparent that such apparatus involves novel and improved means for providing a substantially uniform warning period of operation of a highway crossing signal when a train approaches the crossing, irrespective of the speed of the train.

Although I have herein shown and described only a few forms of railway signal apparatus embodying my invention, it is understood that various changes and modifications may be made therein within the scope of the appended claims without departing from the spirit and scope of my invention.

Having thus described my invention, what I claim is:

1. In combination, a stretch of railway trackway and a traffic controlling device located in said trackway, a train to travel said track, means carried on said train for transmitting to the trackway oscillations modulated in accordance with the train speed, means in the trackway receiving said oscillations, and means jointly governed by the position of said train in said trackway and by the received oscillations for selectively controlling said traffic controlling device to establish a substantially uniform time of operation of such device upon the approach of a train regardless of the train speed.

2. In combination with a stretch of railway track, a traffic controlling device located in the wayside, means responsive to a train on said track for controlling said signal, and means governed by the position of said train on said stretch and responsive to energy applied by said train to the trackway for controlling said first-mentioned means to provide a substantially uniform time interval of operation of said device when a train approaches thereto.

3. In combination, a stretch of railway track adapted to be supplied with energy having a characteristic dependent upon the speed of a train traveling said track, wayside means receiving energy from said track, means operated by said received energy and selectively responsive to the characteristics of said received energy, means responsive to the position of said train on said stretch and a traffic controlling device in the wayside selectively controlled jointly by said energy responsive and position responsive means to provide a substantially uniform interval of operation of said device.

4. In combination, a stretch of railway track,

a train to travel said stretch provided with means for supplying to the rails thereof energy having a frequency proportional to the speed of said train, means in the wayside of said track receiving said energy, a relay operated by said received energy at a rate corresponding to the frequency of such energy, means responsive to the position of said train in said stretch, a signal device in the wayside of said track, and means jointly governed by said train position responsive means and by said relay for controlling said signal to provide a substantially uniform operating interval regardless of the train speed.

5. In combination, a stretch of railway track, a train to travel said track and provided with means for supplying to said stretch energy having a frequency proportional to the speed of said train, means in the wayside of said track for receiving said energy when said train occupies said stretch, means operated by said received energy and selectively responsive to the frequency thereof, means responsive to the position of a train on said stretch, a signal in the wayside, and means jointly controlled simultaneously by said frequency responsive and said train position responsive means for controlling said signal to establish operation thereof when said train reaches one or another of a plurality of positions on said stretch dependent upon the speed of said train.

6. In combination with a stretch of railway track having a track circuit and a signal and means governed by said track circuit for establishing control over said signal when said circuit is occupied, a train to travel said track and having means for impressing on the trackway, energy having a frequency proportional to the train speed, means in the wayside receiving said energy, means operated by said received energy and selectively responsive to the frequency of said energy, and means governed by said last-mentioned means for at times preventing control of said signal by said track circuit means.

7. In a highway crossing signal control system for a stretch of railway track intersected by a highway and having a plurality of track circuits successively entered by a train approaching the intersection, said system comprising a highway crossing signal and means governed by said track circuits for causing operation of said signal, the combination comprising means on a train traveling said track for impressing on the trackway energy having a frequency proportional to the train speed, means receiving said energy from the trackway and selectively responsive to the frequency of such energy, and means governed by said last-mentioned means for at times preventing said track circuit means from causing operation of said signal until said train occupies one or another of said track circuits depending upon the frequency of current applied to the rails.

8. In combination, a stretch of railway track divided into a plurality of successive adjoining track sections, a control device operable to one or another of a plurality of positions according as a train occupies one or another of said plurality of track sections, means for applying to the rails of said trackway energy having a frequency proportional to a condition, means for receiving said energy from the trackway, an operating relay 70 operable by said received energy at a rate proportional to the frequency of said energy, a chain of counting relays including an impulsing relay, means governed by said operating relay for supplying energy to said relay chain for causing op-

eration thereof, and means governed by said control device in accordance with its position for conditioning said relay chain to cause said impulsing relay to operate at a rate having one or another of a plurality of ratios to the rate of operation of said operating relay.

9. In combination, a stretch of railway track divided into a plurality of successive adjoining track sections, a control device operable to one or another of a plurality of positions according as a train occupies one or another of said plurality of track sections, means for applying to the rails of said trackway energy having a frequency proportional to a condition, means for receiving said energy from the trackway, an operating relay operable by said received energy at a rate proportional to the frequency of said energy, a chain of counting relays including an impulsing relay, means governed by said operating relay for supplying energy to said relay chain for causing operation thereof, means governed by said control device in accordance with its position for conditioning said relay chain to cause said impulsing relay to operate at a rate having one or another of a plurality of ratios to the rate of operation of said operating relay, means operated by said impulsing relay and selectively responsive to the rate of operation of such relay, and a signal governed by said last mentioned means.

10. In a railway traffic controlling system, in combination, a source of energy, means for alternately modulating the output of said source at first one and then another frequency of modulation, means governed by a condition for varying the rate at which said energy is alternately modulated, means receiving said modulated energy, a first relay energized from said receiving means when said energy is modulated at said one modulation frequency, a second relay energized from said receiving means when said energy is modulated at said other modulation frequency, said relays being provided with slow releasing characteristics selected to maintain both relays picked up when said energy is alternately modulated at a rate above a predetermined rate, a traffic controlling device, means for operating said device, and means governed by said two relays for at times preventing operation of said device by said operating means.

11. In a railway traffic controlling system, in combination, a source of energy, means for alternately modulating the output of said source at first one and then another frequency of modulation, means governed by a condition for varying the rate at which said energy is alternately modulated, means receiving said modulated energy, a first relay energized from said receiving means when said energy is modulated at said one modulation frequency and having a make-before-break contact arrangement comprising a front contact and a back contact and a bridging member which engages both said front and back contacts when the armature of said relay operates from its released to its attracted position, a second relay and a third relay, an energizing circuit for a winding of said second relay comprising a source of current and said make-before-break contact and a back contact of said third relay, a circuit including a front contact of said second relay or a front contact of said third relay for energizing another winding of said second relay from said receiving means when said energy is modulated at said one modulation frequency, a circuit, including a front contact of said second relay or a front contact of said third relay, for energizing

said third relay from said receiving means when said energy is modulated at said other frequency, said second and third relays being provided with slow releasing characteristics selected to maintain both relays picked up when said energy is alternately modulated at a rate above a predetermined rate, and a traffic controlling device controlled by means rendered effective when both said second and third relays are picked up.

12. In a railway traffic controlling system, in combination, a source of energy, means for alternately modulating the output of said source at first one and then another frequency of modulation, means governed by a condition for varying the rate at which said energy is alternately modulated, means receiving said modulated energy, a first relay energized from said receiving means when said energy is modulated at said one modulation frequency and having a make-before-break contact arrangement comprising a front contact and a back contact and a bridging member which engages both said front and back contacts when the armature of said relay operates from its released to its attracted position, a second relay and a third relay, an energizing circuit for a winding of said second relay comprising a source of current and said make-before-break contact and a back contact of said third relay, a circuit including a front contact of said second relay or a front contact of said third relay for energizing another winding of said second relay from said receiving means when said energy is modulated at said one modulation frequency, a circuit, including a front contact of said second relay or a front contact of said third relay, for energizing said third relay from said receiving means when said energy is modulated at said other frequency, means effective at times to provide said second and third relays with slow releasing characteristics selected to maintain both relays picked up when said energy is alternately modulated at a rate above a predetermined rate, and a traffic controlling device controlled by means at times rendered effective by said second and third relays.

13. In combination, a stretch of railway track divided into a plurality of successive adjoining track sections, a control device operable to one or another of a plurality of positions according as a train occupies one or another of said plurality of track sections, means for applying energy from a source to the trackway of said stretch, means for alternately modulating the output of said source at first one and then another frequency of modulation, means governed by a condition for varying the rate at which said energy is alternately modulated, means receiving said modulated energy, a first relay energized from said receiving means when said energy is modulated at said one modulation frequency and having a make-before-break contact arrangement comprising a front contact and a back contact and a bridging member which engages both said front and back contacts when the armature of said relay operates from its released to its attracted position, a second relay and a third relay, an energizing circuit for a winding of said second relay comprising a source of current and said make-before-break contact and a back contact of said third relay, a circuit including a front contact of said second relay or a front contact of said third relay for energizing another winding of said second relay from said receiving means when said energy is modulated at said one modulation frequency, a circuit, including a front contact of said second relay or a front contact of said third relay,

for energizing said third relay from said receiving means when said energy is modulated at said other frequency, means effective at times to provide said second and third relays with slow releasing characteristics selected to maintain both relays picked up when said energy is alternately modulated at a rate below a predetermined rate, and a traffic controlling device controlled by means rendered effective when both said second and third relays are picked up.

14. In combination, a stretch of railway track divided into a plurality of successive adjoining track sections, a control device operable to one or another of a plurality of positions according as a train occupies one or another of said plurality of track sections, means for applying energy from a source to the trackway of said stretch, means for alternately modulating the output of said source at first one and then another frequency of modulation, means governed by a condition for varying the rate at which said energy is alternately modulated, means receiving said modulated energy, a first relay energized from said receiving means when said energy is modulated at said one modulation frequency, a transformer having a primary winding supplied with unidirectional energy over a front contact of said first relay, a second relay having an energizing circuit supplied with energy of one relative polarity caused to be induced in a secondary winding of said transformer, a third relay, another energizing circuit, including a front contact of said second relay and a back contact of said third relay, for energizing said second relay from said receiving means when said received energy is modulated at said one modulation frequency, a circuit for energizing said third relay by current having the opposite relative polarity caused to be induced in said transformer, another circuit, including a back contact of said second relay and a front contact of said third relay, for energizing said third relay from said receiving means when said received energy is modulated at said other modulation frequency, said transformer and second and third relays being proportioned so that when said first relay operates at a rate above a predetermined rate the energy output of said transformer is insufficient to pick up either said second relay or said third relay, and a traffic controlling device controlled by means rendered effective when both said second and third relays are picked up.

15. In a highway crossing signal control system for a stretch of railway track intersected at grade by a highway and provided with a plurality of track circuits successively entered by a train approaching the intersection, said system comprising a highway crossing signal at said intersection and means controlled by each of said track circuits for causing operation of said signal, the combination comprising means on a train traveling said track for impressing on the trackway, energy having a frequency proportional to the train speed, means receiving said energy from the trackway, a relay operated by such received energy at a rate corresponding to the frequency of said received energy, means operable by said relay for at times preventing operation of said signal by said track circuit means when said received energy has a frequency above a given frequency, and other means operable by said received energy for preventing operation of said signal by said track circuit means when said received energy has a frequency corresponding to a very low or zero speed of the train.

16. In combination, in a system provided for a stretch of railway track for controlling highway crossing signals protecting the intersection of such stretch with a highway, of means on a vehicle traveling said track for supplying the track rails of said stretch with electrical energy modulated in accordance with the vehicle speed, and means in the trackway of said stretch jointly governed by the position of the vehicle in said stretch and by said modulated electrical energy for selectively controlling said highway crossing signals, whereby to establish a substantially uniform time interval of operation of the signals irrespective of the speed of the vehicle traveling said stretch.

17. In combination with a stretch of railway

track, a traffic controlling device disposed in the wayside, a train to travel said track and having means for supplying the trackway with energy having characteristics reflecting the speed of the train, means in said trackway selectively responsive to the characteristics of the energy supplied from said train to said trackway, a plurality of means each responsive to the presence of said train according to its position on said track for controlling said device, and means jointly controlled by said energy responsive and said train responsive means for providing upon the approach of a train a substantially uniform operating period for said traffic controlling device irrespective of the train speed.
